(57) **CLAIM**

We claim the ornamental design for a mobile device, as shown and described.

DESCRIPTION

FIG. 1 is a front perspective view of a first embodiment of a mobile device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view of a second embodiment of a mobile device showing our new design;

FIG. 9 is a front view thereof;

FIG. 10 is a rear view thereof;

FIG. 11 is a left-side view thereof;

FIG. 12 is a right-side view thereof;

FIG. 13 is a top view thereof; and,

FIG. 14 is a bottom view thereof.

The broken lines in the figures depict environmental subject matter and form no part of the claimed design.

The dot-dash broken lines in the figures represent a boundary that forms no part of the claimed design.

The thinner solid lines shown in the figures depict features that are provided beneath the transparent/reflective front surface, where the edges of the transparent/reflective front surface are depicted by the thicker solid lines in the figures.

1 Claim, 10 Drawing Sheets
